S. A. CRONE

LOCKING KEY FOR BRAKE SHOES

Filed June 12, 1922

INVENTOR:

Seth A. Crone
BY
Charles C. Gill,
ATTORNEY

UNITED STATES PATENT OFFICE.

SETH A. CRONE, OF EAST ORANGE, NEW JERSEY.

LOCKING KEY FOR BRAKE SHOES.

Application filed June 12, 1922. Serial No. 567,579.

To all whom it may concern:

Be it known that I, SETH A. CRONE, a citizen of the United States, and a resident of East Orange, in the county of Essex and 5 State of New Jersey, have invented certain new and useful Improvements in Locking Keys for Brake Shoes, of which the following is a specification.

The invention relates to improvements in 10 railway car-brakes and pertains particularly to a novel key for locking the brake-shoe to the brake-shoe head in such manner as to prevent the accidental loss of the key due to the jarring of the train and especially 15 when a car is inverted to discharge its load. The locking key of my invention is applicable to brake-heads and shoes of standard construction and does not call for or necessitate any change in the known and commonly 20 used brake-heads and shoes, but has been specially designed for use therewith and to comply with A. R. A. requirements.

One purpose of my invention is to provide 25 a locking key which may be commercially made and successfully used without any difficulty whatever, the blank for the key having regular continuous side edges and faces and said blank being transformed to provide a head on one end thereof and adjacent to 30 the other end thereof, being formed with a comparatively wide longitudinal slot initially extending uniformly adjacent to said side edges of the blank and thereafter being spread at said edges to provide laterally 35 projecting opposite spring members which retard to some extent the application of the key to operative position and strongly resist the withdrawal of the key but permit such withdrawal on the application of proper 40 force to the head end of the key. The key of my invention is of special design and construction with reference more especially to the features relating to the aforesaid slot and the formation of the spring sides there- 45 at adapted for locking the key in position in the brake-head and shoe, the spring side projections at said slot being near the entering end of the key and of special formation and adapted to yield inwardly on the application 50 of the key to position and thereafter to spread laterally to normal position when arriving below the usual lower lug on the brake-head, the key thus becoming locked in normal operative position securing the 55 brake-shoe to said head.

The invention will be fully understood

from the detailed description hereinafter presented, reference being had to the accompanying drawings, in which:

Fig. 1 is an edge view, and

Fig. 2 a front elevation of a locking key constructed in accordance with and embodying my invention.

In the drawings, 10 designates the key as a whole, and this key is formed from one continuous strip or blank of spring steel and, in the form shown, tapers from its head-end 11 to its entering end 12, both in thickness and in width, the blank or key when in the flat preferably being $13\frac{3}{4}$ inches long, $\frac{3}{8}$ of an inch wide at its head end 11 and $\frac{5}{8}$ of an inch wide at its entering end 12. At its transverse middle the key is $\frac{3}{4}$ of an inch in width. In thickness the key is preferably $\frac{1}{2}$ inch thick at its head end, $\frac{3}{8}$ of an inch thick at its center and $\frac{1}{2}$ of an inch thick at its entering end. The stock from which the key is formed is rolled in the flat to form a blank and thereafter the blank is given the requisite and usual curve, its upper end is bent rearwardly to form the customary head 11 and a longitudinally elongated comparatively wide slot 14 is formed in the blank adjacent to the entering end thereof, this slot being thereafter spread or widened laterally to the condition shown in Fig. 2 and as hereinafter explained. The slot 14 will initially be tapered correspondingly with the adjacent side edges of the key so as to be bounded at its sides by walls of uniform width, and said slot primarily will be, by preference, about $\frac{3}{8}$ of an inch in width at its lower end and $\frac{7}{16}$ of an inch in width at its upper end. After the slot 14 has been formed, the sides of the key at the slot will be spread laterally in a manner to cause the edges of the key at about the transverse middle line of the slot to form outwardly projecting opposite rounded shoulders 15, from the apexes of which the side edges of the key gradually converge downwardly and inwardly on convex curves, as at 16, while at the upper side of the shoulders 15, the edges of the key turn inwardly on somewhat abrupt angles 17 and thence gradually converge upwardly. The slot 14 in its final outline is shown in Fig. 2, and this outline is given to the slot by means of a forming plug forced down into it while the adjacent portions of the key are held in a die defining the form intended for the key at the sides of said slot, the die keeping the side edge portions of the

key at said slot regular and confining the same to the outline shown.

The key 10 is of special character as will be understood from the foregoing description, and the formation of the slot 14 and the spreading thereof to the form shown is for the purpose of providing in an efficient and practical manner, opposite lateral projections, at 15, adapted on being driven through the securing lugs of the head and shoe, not shown, to yield inwardly and thereafter, after passing through the lower lug on the brake-head, to expand outwardly in opposite directions below said lug to resist the upward passage of the key through the lug.

The rolled blank from which the key is formed has the same general proportions as the key, the key differing therefrom only in the curvature of the key, the formation 20 of the bent-over end or head 11 and in the provision of the slot 14 and projections 15. The key may therefore be readily formed from the blank with a minimum of labor and expense. The novel portions of the key 25 are more especially confined to the formation of the slot 14 and of the portions of the key along the side edges of said slot. The slot 14 is initially formed by removing the metal at the interior of the blank or 30 key to provide a substantial opening, as distinguished from merely slitting the blank or key, and in the production of the slot or opening the sides of the blank or key along the same are left narrow and uniform and 35 capable thereafter of being spread and shaped outwardly into the form shown in Fig. 2, whereby said sides are capable of having definite inward spring action on pressure being applied to their outer opposite edges or at the projections 15 and of 40 springing outwardly when such pressure is relieved, these actions of said sides being facilitated from the fact that the ends of the slot are of considerable transverse width. 45 The gentle uniform curvature of the said sides below the projections 15 permit the key to be readily driven through the head and shoe lugs, while the opposite condition above said projections results in the key 50 properly resisting its withdrawal from position. I direct special attention to the fact that in the initial formation of the blank for the key, said blank has regular side edges throughout or in the other words is not 55 formed with side projections to be thereafter used as shoulders, and this feature is one of importance in considering the commercial manufacture of the keys on a large scale.

60 I do not limit my invention in every instance to the specific dimensions of the key hereinbefore recited, nor to the tapering of the sides of the key, nor to the specific formation of the comparatively narrow outwardly spread side edges of the key along

the slot 14, since these features admit of variation within the spirit and scope of my invention as defined in the appended claims. I have shown and described the most desirable embodiment of the invention known to me, and am aware that the same is capable of modification in respect to some of its details.

What I claim as my invention and desire to secure by Letters Patent, is:

1. A locking key of the character described for brake-shoe heads and brake-shoes of standard construction, said key being of elongated and curved form and of stock which is tapered in thickness and in width from the head to the entering end of the key, said key having smooth front and back surfaces allowing, as to themselves, the key to freely pass to and from operative position, and said key having a head at one end and in its lower or entering portion a longitudinally elongated opening which is initially tapered downwardly, being wider at its upper end than at its lower end, and leaving at the sides of the opening substantially uniform narrow integral side edge portions of the key, which portions are in part expanded outwardly in opposite directions to form lateral convex projections adapted to be sprung inwardly in applying the key and thereafter to spring outwardly below the lower brake-head lug, for locking the key in position.

2. A locking key of the character described for brake-shoe heads and brake-shoes of standard construction, said key being of elongated and curved form and of stock which is tapered in thickness and in width from the head to the entering end of the key, said key having smooth front and back surfaces allowing, as to themselves, the key to freely pass to and from operative position, and said key having a head at one end and in its lower or entering portion a longitudinally elongated opening leaving at the sides thereof substantially uniform narrow integral side edge portions of the key, which portions are in part expanded outwardly in opposite directions to form convex shoulders adapted to be sprung inwardly in applying the key and thereafter to spring outwardly below the lower brake-head lug, for locking the key in position, said side edge portions converging downwardly on concave lines from the apexes of said shoulders to facilitate the positioning of the key and forming rather abrupt angles above said shoulders to aid in resisting the withdrawal of the key from its operative position.

3. A locking key of the character described for brake shoe heads and brake-shoes of standard construction, said key being of elongated and curved form and of stock which is tapered in thickness and in width from the head to the entering end

of the key, said key having smooth front and back surfaces, allowing, as to themselves, the key to freely pass to and from operative position, and said key having a head at one end and in its lower or entering portion a longitudinally elongated slot at the middle portions of the sides of which the side edge portions of the key are expanded outwardly in opposite directions to form rounded lateral projections adapted to be sprung inwardly in applying the key and thereafter to spring outwardly below the

lower brake-head lug, for locking the key in position, said side edge portions converging downwardly on concave lines from the apexes of said projections to facilitate the positioning of the key and forming rather abrupt angles above said shoulders to aid in resisting the withdrawal of the key from its operative position.

Signed at New York city, in the county of New York and State of New York, this 9th day of June, A. D. 1922.

SETH A. CRONE.
